DESK MANIFOLDER

Ralph C. Root, Indianapolis, Ind.

Application March 27, 1935, Serial No. 13,257

8 Claims. (Cl. 282—3)

This invention relates to a device adapted to hold a plurality of sheets of paper whereby the sheets may be brought in superimposed relation over a platen with carbon paper therebetween so that a plurality of copies of any desired writing may be had upon making a single impression. This device is commonly termed an autographic register or a manifolder.

It is a primary purpose of my invention to provide such a device in a very simple and light form such that it may be produced and sold at a relatively low price and also such that it may be of a portable nature to be carried about by a billing clerk or a shipping clerk and the like so that the records may be made immediately adjacent the items to be listed.

It is a further primary object of my invention to provide means permitting the easy threading of the various sheets over the platen and then shifting them without tending to shift the carbon sheets out of position or tear their edges as the sheets may be travelled thereover. In this regard I provide a detachable carbon sheet guard which may be readily removed and replaced without the employment of latches or the like.

A still further important object of my invention is to provide a simple presser bar to retain the superimposed sheets in position over aligning pins and at the same time form a tear-off bar. Also an important object of the invention is found in the particular means for mounting the carbon sheet roll so as to retain it in position and at the same time provide the desired tension thereto.

These and other objects and advantages will become apparent to those versed in the art in the following description of the invention wherein one particular form is shown by the accompanying drawings, in which

Fig. 1 is a top perspective view of a device embodying my invention;

Fig. 2, a detail in side elevation of the presser bar tension mechanism;

Fig. 3, a vertical longitudinal section on the line 3—3 in Fig. 1;

Fig. 4, a rear end elevation with portions of the wall broken away;

Fig. 5, a left hand side elevation;

Fig. 6, a longitudinal vertical section similar to that shown in Fig. 3, but with paper shown threaded through the device;

Fig. 7, a view in perspective of one of the carbon sheet guards, and

Fig. 8, a vertical transverse section on the line 8—8 in Fig. 6.

Like characters of reference indicate like parts throughout the several views in the drawings.

I form a generally rectangular box 10 closed on the bottom, sides and top, but having each end open. The top of the box forms a platen 11 and a false bottom 12 within the box is employed, on which bottom 12 a plurality of superimposed zig-zag folded sheets 13 may be carried. I also insert inner walls 14 and 15 along the vertical side walls of the box 10, Fig. 8. The rear end of the platen 11 is sloped downwardly between these side walls 14 and 15 to form the incline 16, Fig. 6. I mount a roller 17 on a shaft 18 having its ends extending through the walls 14 and 15 so that the sheets of paper in the pack 13 may be carried from over that pack around the roller 17, up the incline 16 and across over the platen 11.

The rear end of the box 10 is provided with a door 19 herein shown as being hinged to the bottom of the box 10. The upper end of the door 19 terminates within the plane of the platen 11. A cover 20 is hinged along one side of the box 10, here shown as along the left hand side by the hinge 21. This cover 20 is formed to extend outwardly from the side of the box 10 and thence upwardly and around over the platen 11 and carries a flange 22 fitting downwardly over the upper end of the door 19 and also down over the opposite vertical side wall of the box 10 for a short distance at least. This cover 20 is provided with a central opening over the platen 11 to give that exposure of the forms from the pack 13 as may be desired upon which writing is to be placed.

Within the bulged-out portion of the cover 20 immediately above the hinge 21 on the side of the box 10, I mount a roller or axle 23, Fig. 8, by placing its ends within the V-like notches in brackets 24 and 25 fixed to and extending outwardly from the side wall of the box 10. In order to retain the ends of the axle 23 within these notches, I use a spring 26 secured by its lower end to the side wall of the box and normally pressing against the outer side of the axle end to urge the axle back snugly within the bracket. One such spring is used at each end of the axle 23 at each bracket. In order to remove the axle, all that is necessary is to pull laterally outwardly on the axle to overcome the springs so as to let the axle slip therewith. To replace the axle, the springs are pulled outwardly and the axle inserted therebehind within the brackets.

This axle 23 is employed to carry a roll of carbon paper in one or more superimposed layers, here shown as two layers, Fig. 8, so that the carbon sheets may be pulled from the roll on the

axle and carried transversely across over the platen 11 and then be carried downwardly along the other vertical side of the box 10 as the cover 20 is dropped thereover to compress the ends 5 of the carbon paper against and between the downturned flange 22 of the cover and the side of the box as indicated in Fig. 8. Of course, as fresh carbon paper is desired, the cover may be lifted and the carbon paper pulled over the 10 platen, the cover dropped into place, and then the used paper torn off by pulling up against the under edge of the flange 22.

The forward end of the cover 20 is provided with an upturned flange 27 extending upwardly 15 at the forward end of the opening through the cover. Ahead of the flange 27 is mounted a pressure plate 28 hinged transversely across the forward end of the platen 11, the hinge being immediately adjacent and contacting the upturned 20 flange 27, and further being spaced above the platen 11 sufficiently to permit the desired number of sheets of paper from the pack 13 to slide thereunder. This plate 28 is provided with a plurality of apertures 29, here shown as two in 25 number, to receive therethrough registry pins 30, one through each aperture. These pins 30 are fixed to and carried by the platen 11 to extend upwardly therefrom and at least through the plate 28. The lateral spacing of the pins 30 is that to correspond with the usual apertures 30 (not shown) provided in the customary paper.

In order to retain the plate 28 in its normal position pressing downwardly against what paper may be thereunder and yet to permit the plate 28 35 to be raised when desired, I fix to each end of the shaft 31 to which the plate 28 is fixed, an arm 32, Fig. 2, which has a foot 33 formed and positioned in relation to the plate 28 such that it will strike the under side of the platen 11 to limit 40 the upward travel of the plate 28. The under side of the foot 33 is also formed to ride over a roller 34 on each end of a shaft 35 as the case may be. This shaft 35 has its ends extending through the inner side walls 14 and 15 through 45 slots therein so that the travel of the shaft is confined to a vertical direction. A spring 36 normally pulls the shaft upwardly to its upper limit of travel thereby urging the rollers 34 against the under sides of the feet 33. The under 50 side of each foot 33 is so shaped in the nature of a cam that when the plate 28 is dropped to its lower position, the rollers 34 will be on the forward sides of upturned portions of the feet so as to urge the arms 32 rearwardly and hence pull 55 the plate 28 downwardly. In order to lift the plate 28 from this position, it is then necessary to rock the arms 32 forwardly and thus cause a depression of the shaft 35 overcoming the pull of the spring 36 so that when the plate 28 is 60 then carried to its extreme upper limit of travel, there is another rearwardly and upwardly curved portion on each foot 33 to be then on the forward side of the respective rollers 34 such that the plate 28 is then retained in that upper position. 65

Now in threading the sheets of paper from the pack 13 over the platen 11 and arranging the various sheets of carbon paper therebetween, I first take the top-most sheet on the pack 13 and 70 carry it around over the roller 17 and up over the platen 11 and engage its openings over the pins 30, it being understood that the cover 20 is first lifted upwardly and rocked to the left to be out of the way. Then I pull the carbon 75 paper up from the roll on the axle 23 and take

the under-most sheet thereof and lay it across and over that first sheet of paper placed on the platen 11. A divider 37, generally indicated in Fig. 7, is then placed in position over the rear end of the sheet of paper from the pack 13 and 5 the rear edge of the carbon sheet. This divider 37 consists essentially of a spring-like wire 38 adapted to be bowed upwardly as indicated in Fig. 7 to have its ends inserted through holes provided in the inner walls 14 and 15 so as to 10 have that wire 38 in parallel relation to the roller 17 and sufficiently above the incline 16 to permit the paper sheet to pass thereunder. Attached to the wire 38 is a piece of material flexible in nature, preferably some starched fabric, 15 which is of sufficient length to extend up the incline 16 over the paper sheet and sufficiently over the platen 11 to have it lap over on top of the rear edge of the carbon paper.

Then a second sheet of paper next appearing 20 under the first sheet taken from the pack 13 is carried around over the roller 17, over the divider 37 and up the incline 16 across over the carbon paper on the platen 11 to have its apertured ends engaged over the pins 30. Then a second sheet 25 of carbon paper is laid over on top of this second form sheet and another divider 39 formed in the same manner as the divider 37 has its ends inserted through holes provided in the walls 14 and 15 above and forwardly of those receiving the 30 divider 37. The only difference between the divider 39 and the divider 37 is that the fabric in the divider 39 is of less length so as to terminate substantially immediately above the forward edge of the fabric in the divider 37, but in 35 any event to be of sufficient length to lap over that second sheet of carbon paper.

Then the third form sheet from the pack 13 is brought around the roller 17 and over the divider 39 and up across the platen 11 over the second 40 carbon sheet to have the apertured end of the form sheet engaged over the pins or posts 30. It is to be understood that while I have herein described the threading of the paper as relating 45 to three form sheets superimposed, any desired number may be employed, the three being taken merely as one example to illustrate the method of operation. The form sheets as above indicated are aligned one above the other by the posts 30. The plate 28 is dropped down against the form 50 sheets thus aligned so that the sheets are then retained in the aligned and registered position by pressure of the plate 28 thereover.

After the sheets have been written upon as desired through the opening in the cover 20 the forward ends of the sheets may be gripped by the operator's thumb and finger through an opening 40 cut through the upper central part of the corner of the box 10 and vertical front end. By bringing the operator's finger into the opening 40 60 under the sheets, the sheets may be lifted to lift the plate 28 so that the sheets may be pulled upwardly off of the pins 30 and then pulled forwardly the desired distance until the next set of holes in the form sheets are brought over the pins 30 and dropped down thereover. The plate 28 is then lowered and held in place by hand while the sheets are pulled ahead and then lifted 65 upwardly to have their rear ends torn by shearing along the forward edge of the plate 28. The forward edges of the carbon sheets between the forms terminate, of course, behind the pins 30 so that they are not gripped by the operator's fingers in pulling the sheets ahead and these sheets 70 75

merely slide over and between the carbon sheets without causing any shifting thereof.

Thus it is to be seen that I have produced a very simple device entirely hand operated without the requirement of form shifting means of any sort. By elimination of such mechanism, the device is made to be exceedingly compact and light in weight so that it may be carried around by the operators and be of particular advantage to shipping and billing clerks who want to examine the goods, for example, as the forms are being filled out.

In order to tilt the forward end of the box when the device is to be used on a desk or table and the like, I provide a door 42 in the under side of the box at its forward end, Fig. 3, hinged to drop down by the forward end so as to form a leg to lift the front end of the box. Thus when this door is opened as indicated, the rear end of the box will rest on the table while the lower end of the door will also rest thereon thereby tilting upwardly the forward end of the box.

While I have herein shown and described my invention in the best form as now known to me, it is obvious that structural changes may be made without departing from the spirit of the invention, and I, therefore, do not desire to be limited to that precise form beyond the limitations as may be imposed by the following claims.

30 I claim:

1. A manifolding device comprising a box having side walls formed of two spread apart members, said box adapted to hold a pack of zig-zag folded superimposed sheets having registering apertures, a platen having a downwardly inclined rear end, said box having means for holding a supply of one or more carbon papers along a side of the box whereby the paper may be carried laterally across the platen to have a carbon paper between sheets laid over the platen, and a divider for each carbon paper placed between two of said sheets transversely of the platen toward the rear end thereof to lap over the rear edge of the paper between the sheets whereby the sheets may be shifted ahead without dragging on said carbon paper edge, said divider being formed to have a spring member engaging by its ends in apertures in the inner side walls of the box whereby the member will be held from longitudinal movement by the outer walls but may be bowed to reduce its effective length to permit disengagement from said apertures and an apron extending from the spring member to form said lap the divider member being located below the plane of the platen in the space above the inclined rear end of the platen.

2. A manifolding device comprising a box adapted to hold a pack of zig-zag folded, superimposed sheets each having registering apertures, said box having a platen, with pins fixed at the forward end of the platen to receive and register said apertures when said sheets are carried over the platen, a presser plate hinged to said box to drop over said sheets about said pins, cam means yieldingly holding said plate selectively in a lowered position against the sheets and in a raised position removed from the sheets, said plate serving both to releasably retain said sheets in register over said pins and as a sheet tear-off bar when raised.

3. A manifolding device comprising a box adapted to hold a pack of zig-zag folded superimposed sheets having registering apertures, a box lid having flanges at the sides of the box, a platen, 75 said box having means for holding a supply of

one or more carbon papers along a side of the box whereby the paper may be carried laterally across the platen and clamped between a lid flange and box side and torn against the flange to have a carbon paper between sheets laid over the platen, and said box having a divider for each carbon paper placed between two of said sheets transversely of the platen toward the rear end thereof to lap over the rear edge of the paper between the sheets whereby the sheets may be shifted ahead without dragging on said carbon paper edge, brake means in said carbon paper holder for holding the carbon papers at that end so they will be tightened against the paper sheets by clamping the carbon paper between the box side and lid flange, the rear end of said platen having an inclined portion, a roller at the lower edge of the inclined portion and said divider being mounted across said portion to extend upwardly thereover and over said platen.

4. In a manifolding device, sheet registering pins, a presser and tear-off plate hinged to drop over said pins, an arm fixed to rock with the plate, a cam on the arm, a bar over which the cam rides, said bar being mounted to be reciprocable toward and away from said plate in the path of said cam, and spring means urging the bar toward said plate, said cam being formed to cause said plate to yieldingly remain in either a down or an upper position by pressure of said bar thereagainst.

5. In a manifolding device comprising a box, and a platen having sheet registering pins, and having a presser and tear-off plate hinged to drop over the pins, a cover having a central opening over the platen terminating with a member turned up sharply to form a stiffening flange for and against the hinge of the tear-off plate.

6. In a manifolding device, a box having a door at one end hinged to swing downwardly to raise that end and having a door at the other end hinged to swing outwardly and downwardly, and having a platen and also having a pressure and tear-off plate hinged to the platen in combination with a cover for the box having a flange at one end to lap over and hold the second door in closed position of the door, said cover having a central opening terminating with a member turned up vertically to form a stiffening flange for and against the hinge of the tear-off plate.

7. In a manifolding device comprising a box having outer and inner side walls with holes through the inner walls in combination with a platen in the box having an end portion bent angularly downward, a carbon paper edge protector comprising a flexible spring wire mounted in the space above the downwardly bent portion of the platen and a fabric attached to the wire to extend laterally therefrom across the angular bend in the platen and to leave a length of wire extending at each end from the fabric which ends are inserted through corresponding holes in opposite inner walls and are held from longitudinal movement by contact with the outer walls of the box.

8. In a manifolding device, a box having therein a platen, means for feeding paper strips from front to rear of the box over the platen and means for supplying carbon paper between the paper strips in combination with a door under the box and hinged to the front end of the box to swing downwardly and raise that end of the box while that end of the box is closed.
